PACKAGED EDUCATIONAL BOARD TOY

Robert I. Genin, New Rochelle, and Leon S. Wirch,
Forest Hills, N.Y., assignors to Child Guidance Toys,
Inc., Bronx, N.Y., a corporation of New York

Filed Aug. 10, 1961, Ser. No. 66,286

Term of patent 7 years

(Cl. D25—1)

Fig. 1

Fig. 2

FIGURE 1 is a front elevational view of a packaged educational board toy showing our new design,

FIG. 2 is a front perspective view thereof.

The dominant feature of our design resides in the portions shown in full lines and consists essentially in the figure of a child in a lower section affixing a full scale letter, numeral or the like on the blank area substantially as shown.

We claim:

The ornamental design for a packaged educational board toy, substantially as shown and described.
